UNITED STATES PATENT OFFICE.

JOHN D. PUGH, OF BALTIMORE, MARYLAND.

FURNACE-STOCK DISTRIBUTER.

No. 827,118.

Specification of Letters Patent.

Patented July 31, 1906.

Application filed September 8 1905. Serial No. 277,626.

To all whom it may concern:

Be it known that I, JOHN D. PUGH, a citizen of the United States, residing at Baltimore city, State of Maryland, have invented 5 certain new and useful Improvements in Furnace-Stock Distributors, of which the following is a specification.

This invention comprises means for distributing the stock evenly in charging-receptacles, as the hoppers of blast-furnaces. The invention may of course be utilized in other apparatus in which materials are to be evenly distributed, and especially in apparatus wherein several different kinds of materials 15 are required to be mixed more or less uniformly.

The invention will be described in connection with the accompanying drawings, in which—

20 Figure 1 is an elevation, partly in section, illustrating the upper part of a blast-furnace and the present improved means for charging the same. Fig. 2 is a detail of the means for turning the bucket of the conveyer. Fig. 3 is a vertical section through the bucket on the line 3 of Fig. 1. Fig. 4 is a plan view of the means for operating the cones which trap the material into the furnace. Fig. 5 is a sectional view through a portion of the apparatus, and Fig. 6 is a detail of the ratchet mechanism.

25 Referring to the drawings, 10 indicates the upper part of the furnace structure; 11, a chamber in which the material is temporarily held before being dumped into the furnace; 12, a cone or closure for the lower end of the hopper, and 13 a cone or closure separating the chamber 11 from the hopper 14 and forming a bottom for the latter.

30 The upper cone 13 is connected by a link with a lever 15 and also connected by similar links with a guide-arm 16. The lever 15 is provided with a counterweight 17, and, as shown, it is operated by means of a power cylinder 18 and a piston-rod 19. The cylinder 18 constitutes a motor, which may be operated by steam, compressed air, or hydraulic power in any suitable manner. When the piston-rod 19 is raised, the cone 13 is lowered 35 to discharge the contents of the hopper, as shown in dotted lines in Fig. 1, and the cone is closed by operating the piston-rod in the reverse direction. The radial arm 16, which moves in synchronism with lever 15, by means of the shafts and miter-wheels shown in plan, Fig. 4, prevents the cone from being

swung to one side by the lever 15—that is, it guides it in a vertical line—the effect of the arm and lever upon the cone being equal and opposite.

40 The lower cone 12 is provided with a transverse bar 20, which is connected by links 21 with the ends of a pair of levers 22. These levers are pivoted at 23 upon brackets supported by the furnace structure. The outer 45 ends of the levers converge and are connected with a cross-head 24, which in turn is connected to a piston-rod 25, operating in a motor-cylinder 26, similar to the cylinder 18. On the piston-rod 25 is a suitable counter-weight 27. The raising and lowering of the piston-rod 25 effects the opening and closing of the cone 12 in an obvious manner.

45 The parts above described constitute no part of the invention herein claimed and are 50 set forth to illustrate one arrangement of top filling mechanism of a furnace with which my invention may be combined, but which may be varied indefinitely.

55 With any construction and arrangement 55 of top devices I combine my improvement, which consists, essentially, of a bucket, means for carrying it to and from the furnace-top, and means whereby the contents of the bucket are discharged therefrom laterally, 60 but at successive discharges in different lateral positions. Different arrangements may be used to thus discharge the contents of the bucket; but, as shown, the bucket is adapted to discharge material or stock into one side 65 of the receptacle or hopper 14 and is automatically turned to distribute its contents at different points of the receptacle, the bucket being adapted to travel between the hopper and the source of supply of material for the 70 furnace and to discharge its contents laterally with respect to the axis upon which it turns. By means of the fractional turning of the bucket, which is accomplished automatically, stock is dumped successively at 75 different points in the hopper and distributed in any desired manner therein. The bucket 28 is shown in Fig. 1 arranged centrally over the hopper 14. It has an inclined bottom 29 and a door 30, which may be opened or 80 closed in any suitable manner. The bottom of the bucket extends over the center of the hopper and is adapted to discharge the contents of the bucket at one side of the hopper. The bucket 28 is provided with an overhanging flange 31, and between the flange and the bucket proper are three or more wheels 32,

which run on a circular rail or ring 33, the bucket being thus supported on said ring. The ring 33 is supported on trunnions 34 35, being part of said ring and having bearings in brackets 36 on the forward end of a car 37. 5 These trunnions insure the bucket always hanging in a vertical position independent of the position of car in traveling to and from source of supply. The car is simply a framework suitable for carrying the bucket and provided with two pairs of wheels. The forward or upper wheels 38 run on rails 39, while the rear or lower wheels 40 run on rails 41 of broader gage. The upper ends of the rails 10 39 are curved over the furnace and terminate in upward bends 39^a, which form stops for the forward wheels, and the rails 41 have branches 42 at their upper ends which guide the wheels 40, the wheels 40 being prevented 15 from leaving the rails 41 by means of the rails 42. The curved connecting portion 41^a of the rails 41 42 form stops for the wheels 40. The car 37 may be operated by a cable 43, running over a sheave 44, or by any other 20 suitable means for elevating a car. When 25 the car reaches its uppermost position, in which the wheels are retained by the bends 39^a 41^a, the bucket will be located centrally over the hopper 14, as shown in Fig. 1.

30 I provide means for rotating the bucket automatically through a portion of a circle between successive discharges. This rotation may be effected just before or after the discharge of the bucket or at any time during 35 the travel of the bucket from the hopper to the source of supply of material and back again. As shown, the bucket is rotated step by step by the following means: Upon the bucket, below its supporting-wheels 32, is a 40 bevel-gear 45, extending entirely around bucket. In mesh with this gear is a bevel-pinion 46 on a shaft 47, extending centrally through the trunnion 35 of the ring 33. Upon the shaft 47 is fixed a ratchet-wheel 48, and 45 loose upon the shaft, outside of the ratchet-wheel, is a gear 49. The gear carries a pawl 50, which is adapted to engage with the ratchet-wheel 48 when the gear is rotated in one direction and which rides freely over the 50 teeth of the ratchet-wheel when the gear is rotated in the opposite direction. The gear 49 is adapted to intermesh with a short curved rack 51, arranged on a part 52 of the 55 fixed frame. The rack 51 is parallel with the curved path in which the trunnions of the car travel in approaching their central position over the hopper 14.

60 The operation of rotating the bucket step by step is as follows: As the car 37 is lowered from the position shown in Fig. 1 the gear 49 is rotated by the rack 51, and the bucket is thereby rotated through a fraction of a circle by means of the pawl-and-ratchet connection described, the shaft 47, pinion 46, and gear 65 45, the bucket traveling on the ring-rail 33.

The bucket retains the position to which it is turned while it travels to the source of supply of stock and back to the hopper. As it approaches the hopper it will not be affected by the rack 51, as the reverse movement of 70 the gear 49 simply causes the pawl 50 to ride freely over the ratchet-wheel 48. It will be understood that by simply reversing the ratchet-wheel the bucket would be turned as it approaches the hopper; but this is not so 75 desirable, as it is preferable to turn the bucket while it is empty. It will also be understood that my invention consists, broadly, in mechanism for rotating the bucket to enable it to discharge its contents at different points 80 regardless of the particular devices employed.

Without limiting myself to the construction and arrangement shown, I claim—

1. The combination with means for conveying a bucket to and from a receptacle, of 85 a bucket supported by said means, means for discharging the contents of the bucket laterally, and means for turning the bucket to insure the discharge of its contents in different directions. 90

2. The combination with a receiving-hopper, of a bucket, means for conveying the bucket to and from the hopper, means for discharging its contents at one side of the hopper, and automatic means for turning the 95 bucket to insure the deposit of the discharged material at different parts of the hopper.

3. The combination with a receiving-hopper, of a bucket, a car upon which the bucket 100 is carried to and from the hopper, the said bucket being rotatably mounted on said car, and means for rotating the bucket between successive discharges thereof, said bucket being arranged to discharge its contents laterally with respect to the axis upon which it turns. 105

4. The combination with a receiving-hopper, of a bucket, a car upon which the bucket is carried to and from the hopper, the said 110 bucket being rotatably mounted on said car, means for rotating the bucket between successive discharges thereof said means comprising a rack and gear, and a ratchet connection between said gear and the bucket, 115 said bucket being arranged to discharge its contents laterally with respect to the axis upon which it turns.

5. The combination with a receiving-hopper, of a car, a ring carried by the car, a 120 bucket supported by wheels or rollers upon said ring, and automatic means for rotating the bucket, for the purpose set forth, said bucket being arranged to discharge its contents laterally with respect to the axis upon 125 which it turns.

6. The combination with a receiving-hopper, of a car adapted to travel to and from the furnace, a ring having trunnions mounted on said car, a bucket supported by suit- 130

able wheels upon said ring and rotatable thereon, a fixed rack in the path of the bucket, and gearing operated by said rack and adapted to turn the bucket, for the purpose set forth, said bucket being arranged to discharge its contents laterally with respect to the axis upon which it turns.

7. The combination with a receiving-hopper, of a car traveling to and from said hopper, rails for guiding said car, means for stopping the car in proper relation to the hopper, a bucket supported on the car and adapted to turn thereon, a fixed rack in the path of the car, a gear carried by the car and adapted to engage with said rack, and connections between the gear and the bucket for turning the latter automatically as the car is moved, said bucket being arranged to discharge its contents laterally with respect to the axis upon which it turns.

8. The combination with means for conveying a bucket to and from the top of a furnace, of a bucket having an opening arranged to discharge the contents laterally therefrom, said bucket rotatable upon its vertical axis.

9. The combination with a receiving-hopper, of a bucket, a car upon which the bucket is carried to and from the hopper, and means for moving the bucket relatively to the car between successive discharges thereof, whereby the bucket is made to discharge its contents successively to different parts of the hopper.

10. The combination with means for carrying a bucket to and from the receiving-hopper of a furnace, of a bucket, and means whereby to discharge the contents of said bucket laterally therefrom in different positions.

11. The combination with means for carrying a bucket to and from the receiving-hopper of a furnace, of a bucket provided with lateral discharging means, and means whereby to direct the discharges successively in different positions.

12. The combination with a car and means for carrying it toward and from the top of a furnace, of a bucket mounted on the car and provided with a discharge-opening, and means for directing successive discharges from the bucket in different positions laterally.

13. The combination with a car and means for carrying it toward and from the top of a furnace, of a bucket mounted rotatably on the car and provided with a lateral discharge-opening.

14. The combination with a car and means for carrying it toward and from the top of a furnace, of a bucket mounted rotatably on the car and provided with a lateral discharge-opening, and means for automatically turning the bucket a part rotation on each travel of the car.

15. The combination with means for conveying a bucket to and from a receptacle, of a bucket supported by said means, means for discharging the contents of the bucket laterally, and means for automatically turning the bucket to insure the discharge of its contents in different directions.

In testimony whereof I have signed my name to this specification in the presence of two subscribing witnesses.
